UNITED STATES PATENT OFFICE.

GEORGE HAVELL, OF NEWARK, NEW JERSEY, ASSIGNOR TO HARVEY S. ALMY, OF NEW YORK, AND GEORGE W. ALMY AND WILLIAM D. CHASE, OF BROOKLYN, N. Y.

DESIGN FOR CLOCK-CASE.

SPECIFICATION forming part of Design No. 11,730, dated April 13, 1880.

Application filed February 19, 1880. Term of patent 7 years.

To all whom it may concern:

Be it known that I, GEORGE HAVELL, of Newark, in the county of Essex and State of New Jersey, have invented a new and original 5 Design for a Clock-Case, of which the following is a specification.

My invention relates to a new and original design for clock-cases; and it consists in the new configuration of the case, as hereinafter 10 described.

The accompanying drawing represents a perspective view of my improved design.

The top A of the clock-case has its edges a curved downward and outward, so as to project beyond the sides of the dial-carrying 15 body B of the said case, forming thus a pagoda-like top to the case.

The bottom D of the case likewise projects

beyond the sides of the case, with a downward and outward or concave curved edge, b, and to the under side of the curved bottom edge, b, are fixed the spherical feet d, by which the clock-case is sustained above the surface on which it is placed.

The entire clock-case has a pagoda-like appearance.

I claim—

The design for a pagoda-shaped clock-case, consisting of a straight-sided central dial-carrying body, B, an outwardly-sloping curved base, b, and a downwardly-sloping curved top, a, substantially as shown.

GEORGE HAVELL.
